UNITED STATES PATENT OFFICE.

CHARLES DAWSON, OF PADEN CITY, WEST VIRGINIA.

GLASS-ROLLING APPARATUS.

1,841,547.

Specification of Letters Patent. Patented May 25, 1920.

Application filed May 29, 1918. Serial No. 237,355.

To all whom it may concern:

Be it known that I, CHARLES DAWSON, a citizen of the United States, residing at Paden City, in the county of Wetzel and

5 State of West Virginia, have invented new and useful Improvements in Glass-Rolling Apparatus; of which the following is a specification.

This invention relates to glass rolling apparatus and more especially to apparatus designed to embed wire mesh in the sheet of glass being rolled.

One object is to provide improved means for regulating the feeding of the wire mesh, 15 and another object is to provide a roll of novel construction designed to press the wire into the glass after it has passed under a roll regulated to gage the thickness of the glass.

20 A further object is to provide, in a machine of the type described, a roll comprising a plurality of spaced disks arranged at an angle, or inclined, with reference to the longitudinal axis of the roll, these disks acting on the wire mesh and pressing the latter into the glass in a more uniform and effective manner than a roll of the ordinary construction.

A still further object is to provide a water 25 cooled table carrying rack bars on the upper and lower surfaces thereof, means being provided for engaging the aforesaid lower rack bars and giving a more uniform and even drive than is possible in the use of a machine in which the drive is through rack bars carried only by the upper portion of the table.

A still further object is to provide for 30 driving the rolls from the rack bars carried by the upper surface of the table.

A still further object is to provide an apparatus designed to produce a larger output than the machines ordinarily in use, the number of assistants required being less 45 than customarily employed.

With the foregoing and other objects in view, this invention consists in the novel construction, combination, and arrangement of elements hereinafter described and claimed.

50 Figure 1 is a view in side elevation.

Fig. 2 is a top plan view.

Fig. 3 is a vertical transverse section.

Fig. 4 is a further transverse section showing the wire mesh being fed into the apparatus.

55 Fig. 5 shows one of the bearings for the rollers adjustable lengthwise of the frame.

Fig. 6 is a detail showing means for raising one of the rollers controlling the wire mesh.

60 Fig. 7 is a detail view of the device for regulating the width of the sheet of glass being rolled.

A plurality of standards 10 support upper spaced longitudinal side bars 12 carrying the rolls, these rolls being designated 13, 14, 15, and 16, and being mounted in journal boxes shown at 17, the latter being retained within frames 18, 19, 20, and 21, carried by the main supporting structure, 65 70 and directly carried by bars 12. Each roll is adjustable by means of a hand wheel 23 controlling a screw 24.

The roll 15 is of special construction and is of the water cooled type, including a hollow axle 25 on which is mounted a series 75 of disks 26, arranged at an incline with reference to the longitudinal axis of the roll. A collar 27, is carried by each end of the roll and is thicker at one side than at the other, thereby providing for the inclination of the disks.

In practice the disks are about 12" in diameter, and are made from rolled steel, the thicker portions thereof being above $\frac{1}{8}$ 85 of an inch and the thinner outer portions about $\frac{1}{16}$ of an inch in thickness. This is a convenient way of effecting the spacing of the disks at their edges.

Each roll is provided with gear wheels 90 such as 30 and 31 at the opposite ends thereof, these rolls being driven by means of the upper rack bars 32 carried by the traveling table 35. The roll 16 controls the thickness 95 of the glass before it passes under the roll 15, and before the wire mesh is applied.

The wire mesh is shown at 36 and passes between rolls 37 and 38, the upper roll being adjustably mounted and being under the control of pivoted arms 39, mounted in 100 brackets 40. These arms are downwardly deflected and are controlled by means of

elevated portions 41 carried by the table at the proper point to effect the lifting of the upper roll 37 when desired.

The rolls 13 and 14 act upon the glass 5 with the wire embedded therein and serve to resurface the sheet.

The upper roll remains in an elevated position until the sheet of glass is engaged by corrugated roller 15. The cams 41 then 10 pass from beneath arms 39 and allow upper roll 37 to drop, the weight of the roll tightening the wire mesh while the sheet is being rolled. Upper roll 37 is again raised by elements 41 before a new sheet is engaged 15 by corrugated roll 15.

The table 35, of the water cooled type, is of steel and is mounted between longitudinally extending channel bars designated 45, these bars being supported, by frame 46, and 47, on each side of structure, the frames in turn carrying brass journal boxes mounting the axles 48, and 49, of wheels 50. The track on which the structure travels is designated 51. An intermediate frame 52, is 25 located on each side of the structure, and the elements 46, 47, and 52 support the lower rack bar, or bars, 53. These rack bars are engaged by gear wheels 55 carried upon an axle 56, driven from any suitable 30 source of power.

The water cooled table 35 is provided at each end with a hood 60 having inlet member 61 connected therewith, and the table proper is provided with a plurality of longitudinal channels 62 through which the water circulates. An inclined plate 63 is located as shown.

The journal boxes and their supporting elements are shown in detail in Figs. 1, 2 40 and 5, and it will be observed that the brasses are grooved and held in position between vertical side members of the frame, and that coil springs are provided as shown at 65 and bear against the ends of the adjusting screws 24, in order to provide necessary resiliency in the event that any hard 45 substance carried by the molten glass comes into contact with the rolls. The width of the glass is regulated by suitable devices 50 shown in Fig. 7.

Fig. 7 shows the device for regulating the width of the glass sheet, this device including the transverse rod 75 having connected therewith by means of eye members 76 and 55 77, bars 78 and 79, provided with curved ends 80. Bars 78 and 79 support transverse bars 81 and 82 secured to bar 79, the elements 81 and 82 being slotted at one end to permit of adjustment.

60 The guides 84 and 85 control the width of the sheet of glass, guide 84 and bar 78 being adjustable on rod 75.

A table over which the wire mesh travels is designated 70, and it may be added that

guiding devices engaging the rolls 13, 14, 15, 65 and 16, and maintaining proper alinement are shown at 71.

What is claimed is:

1. In an apparatus of the class described, a traveling table, a supporting structure, a plurality of rolls carried by said structure, and means for embedding wire mesh in a sheet of glass being rolled, said means comprising a corrugated roll formed of disks arranged at an incline with reference to the 75 axle of the roll and angular elements of tapering cross section abutting the end disks of the roll and determining the angle of inclination of all of the disks.

2. In an apparatus of the class described, 80 a traveling table, a supporting structure, a plurality of rolls carried by said structure, means for supporting wire mesh, means for guiding the wire mesh, and means for pressing the latter into a sheet of glass being 85 rolled, said means last named comprising a water cooled roller including a plurality of disks spaced apart at their peripheries, and inclined with reference to the main axis of the roll and angular elements of tapering 90 cross section abutting the end disks of the roll and determining the angle of inclination of all of the disks.

3. In an apparatus of the class described, 95 a traveling table, a plurality of rolls, a structure for supporting said rolls, means for driving the rolls by the movement of the table, means for supporting a wire mesh, means for feeding the mesh into a sheet of plastic glass being rolled and width determining means comprising a frame formed of pivotally mounted side bars, said bars having curved portions extending over one of the rolls, slotted transverse bars connecting the side bars and adjustable with reference thereto, and parallel elements suspended from the frame and having blade formation.

4. In an apparatus of the class described, 110 a traveling table, a plurality of rolls, a supporting structure therefor, means for supporting a wire mesh, and means for feeding said mesh and comprising a plurality of rolls, the upper roll being vertically movable, a plurality of pivotally mounted arms 115 for controlling the position of the upper roll, and means moving with the table for raising the arms and upper roll, until a predetermined length of glass has been fed.

5. In an apparatus of the class described, 120 a traveling table, a plurality of rolls, a supporting structure therefor, means for supporting a wire mesh, and means for feeding said mesh and comprising a plurality of rolls, the upper roll being vertically movable, a plurality of pivotally mounted arms 125 for controlling the position of the upper roll, and means carried by the table for rais-

ing the arms and upper roll, until a predetermined length of glass has been fed, said roll last named being grooved annularly near its ends and the arms operating within 5 said grooves.

6. In a device of the class described, a traveling table, a plurality of rolls, means for feeding a wire mesh and comprising a

plurality of rolls one of which is vertically movable, and means controlled by the position of the table, for raising the roll last named, until a predetermined length of glass has been fed. 10

In testimony whereof I affix my signature.

CHARLES DAWSON.
